SWITCH OPERATING MECHANISM AND FAN

Clarence R. Aben, River Rouge, Mich.

Application February 28, 1947, Serial No. 731,485

2 Claims. (Cl. 318—221)

1

My invention relates to a new and useful improvement in a combination switch operating mechanism and fan adapted for use on electric motors and the like.

In certain type motors, the construction of the stator comprises of a running and a starting winding which are both energized at the start until the rotor has obtained sufficient speed to develop the proper torque at which time a switch associated with the rotor will, by centrifugal action, be actuated for breaking the circuit to the starting winding. The present invention is directed to this switch mechanism and an object of the present invention is to provide both a mechanism for operating the switch responsive to centrifugal action and whereby the centrifugal force will maintain the mechanism in such position that it will serve as a fan blade or vanes for moving air through the casing of the motor.

It is another object of the present invention to provide a mechanism of the class described and which is simple in construction, economical of manufacture, durable, and highly efficient in use.

It is still another object of the present invention to provide a combination switch mechanism and fan for electric motors of the class described having vanes or blades mounted on the end of the rotor and pivotally connected thereto so that as the rotor is rotated, centrifugal force will rock the blades or vanes to lie adjacent the periphery of the rotor to act as blades for moving air through the casing, and to permit the axial movement of a sleeve on the rotor shaft for actuating a switch breaking the electrical circuit to the starting winding of the motor.

Other objects will appear hereinafter.

It is recognized that various modifications and changes may be made in the detail of structure illustrated without departing from the invention itself and it is intended that such shall be embraced within the scope of the claims which form a part hereof.

Forming a part of this specification are drawings in which:

Fig. 1 is a top plan view of a motor.

Fig. 2 is a sectional view taken along line 2—2 with the invention applied and illustrating its position when the motor is at a stand still.

Fig. 3 is a sectional view taken on line 3—3 illustrating the invention when the rotor has obtained a predetermined speed.

Fig. 4 is a fragmentary, sectional view taken on line 4—4 of Fig. 2.

Fig. 5 is an enlarged fragmentary, sectional view taken on line 5—5 of Fig. 2.

2

Fig. 6 is a fragmentary, sectional view taken on line 6—6 of Fig. 2.

Shown in the drawing is an electric motor comprising the stator iron 7 enclosed in a casing 8 having an end housing 9 in which is provided a bushing 12 in which is bearinged the reduced end 13 of the rotor shaft 14. The rotor 15 is secured on the shaft 14. A running winding 10 and a starting winding 11 is coiled through the stator iron 7.

Secured on the end wall of the rotor 15 are the lugs 16 and 17. These lugs 16 and 17 are mounted in spaced radial alignment on the rotor and pivotally secured to the lug 16 by the rivet 18 is one end 15 of link 20, and a link 21 is pivotally secured by the rivet 19 to the lug 17. The opposite end of the link 20 is pivotally secured by a rivet 22 to the vane or blade 24, and the opposite end of the link 21 is pivotally secured by the link rivet 23 to the 20 vane or blade 24. Resting on the curved edge 25 of the vane or blade 24 is the flange 28 extended laterally of the collar 27 that is slidably mounted on the shaft 14. Extended outwardly from a face 25 of the vane or blade 24 is a stud 30 to which one 20 end of a spring 29 is secured and the opposite end of which is secured to the collar 27. When the rotor is at rest, the spring 29 serves to hold and move the blade or vane 24 towards and against the collar 27 with the flange 28 resting 30 upon the curved edge 25.

In engagement with the flange 28 are one end of the yoke arms 31 which are pivotally supported by the pin 32 on the bracket arm 33. The yoke arm 31 is provided with extension 34 which projects 35 rearwardly of the pivot pin 32 and adapted to engage one end of a resilient arm 35 which carries a contact point 36 adapted to engage the contact point 37 on a resilient arm 38. The opposite end of the arms 35 and 38 are secured together and 40 insulated from each other by insulating blocks 39 and secured to the end casing 9 by the screws 40. The arm 35 is connected by a suitable wire 41 and the arm 38 by a suitable wire 42 which forms a circuit to the starting winding (not shown).

45 In operation, when the rotor is at rest, the vanes will be in the position shown in Fig. 2 held by the spring 29 towards and against the collar 27 and holding the collar 27 so that the yoke arms 31 are rocked upwardly against the 50 tension of the contact arm 35 which is moved by the extension 34 so that the contact points 36 and 37 are together for closing the circuit to the starting winding. Upon the rotor obtaining a predetermined speed where it has developed a required torque, the vane or vanes 24 will be 55

moved, against the tension of the spring 29, by centrifugal force to swing outwardly into the position shown in Fig. 3 so that the edge 45 of the vane will lie in alignment with or just below alignment with the periphery of the rotor 15. Further movement of the blade outwardly by centrifugal force is prevented by the link arm 21 striking against the arm 20 which serves as a stop against further rocking movement of the link 21 and thereby preventing further rocking movement of the link 20. As the vane 24 moves outwardly, the radius edge 25 would be so tilted that the point 26 will move downwardly permitting a downward axial movement of the collar 27 towards the end of the rotor 15 permitting the yoke arms 31 to follow and rock the extension 34 away from the resilient arms 35 permitting it to snap upwardly moving the contact point 36 away and out of contact from the point 37 thereby breaking the electrical circuit to the starting winding 11.

As the vane or vanes 24 are held outwardly by centrifugal force, they would act as a fan for the drawing of air inwardly through the opening 43, formed in the casing 9 and caused to pass outwardly with the heated air within the motor casing through the opening 44, formed in the casing 9. Any number of vanes may be radially positioned on the end of the rotor 15 as the number depends upon the size of the motor, the quantity of air that is desired to be moved through the casing, and the size of the vanes that are to be constructed.

What I claim as new is:

1. A device of the class described adapted for use with an electric motor having a rotatable shaft, a rotor fixedly mounted on said shaft, a driving winding and a starting winding, comprising: a switch for controlling a circuit to said starting winding; an arm for pressing said switch into closing position; a plurality of pairs of circumferentially spaced apart lugs mounted on one of the end faces of said rotor, the lugs in each pair being in radial alignment and spaced apart to provide an inner lug and an outer lug; a link pivotally mounted on one end to said outer lug; a plate, said link being pivotally connected at its opposite end to said plate adjacent one end; a second link pivotally connected at one of its ends to the other of said lugs in the pair and pivotally connected at its opposite end to said plate adjacent the opposite end of said plate; a collar slidable on said shaft; a peripheral flange on one end of said collar for engaging at one face said arm and upon moving

5 in one direction axially of the shaft for moving said arm to close said switch, said plate being engageable with the opposite face of said flange; and a spring connected at one end to said collar and at its opposite end to said plate for normally moving said plate on its links and to normally retain said collar in position for effecting the closing of said switch.

2. A device of the class described adapted for use with an electric motor having a rotatable shaft, a rotor fixedly mounted on said shaft, a driving winding and a starting winding, comprising: a switch for controlling a circuit to said starting winding; an arm for pressing said switch into closing position; a plurality of pairs of circumferentially spaced apart lugs mounted on one of the end faces of said rotor, the lugs in each pair being in radial alignment and spaced apart to provide an inner lug and an outer lug; a link pivotally mounted on one end to said outer lug; a plate, said link being pivotally connected at its opposite end to said plate adjacent one end; a second link pivotally connected at one of its ends to the other of said lugs in the pair and pivotally connected at its opposite end to said plate adjacent the opposite end of said plate; a collar slidable on said shaft; a peripheral flange on one end of said collar for engaging at one face said arm and upon moving in one direction axially of the shaft for moving said arm to close said switch, said plate being engageable with the opposite face of said flange; and a spring connected at one end to said collar and at its opposite end to said plate for normally moving said plate on its links and to normally retain said collar in position for effecting the closing of said switch, said plate being adapted, upon rotation of said rotor at a predetermined speed, for swinging outwardly of said rotor on its links for sliding said collar axially of the rotor and effecting an opening of said switch, the edge of said plate engaging said flange being curved.
